HEEL ATTACHING MACHINE

Arthur Alan Rivington and Lionel William Gayton Wilkinson, Leicester, England, assignors to United Shoe Machinery Corporation, Flemington, N. J., a corporation of New Jersey

Application January 15, 1953, Serial No. 331,410

Claims priority, application Great Britain February 13, 1952

7 Claims (Cl. 1—32)

This invention relates to heel attaching machines and is illustrated as embodied in a machine having a work support which is similar to the work support disclosed in United States Letters Patent No. 2,428,047 granted September 30, 1947 on an application filed in the name of John F. Standish, but which is modified to adapt it for driving a nail, drive screw, or similar fastening, through the pin-hole of a last, and the heel seat of a shoe upon the last into a heel, to attach the heel to the shoe.

The present invention consists in the novel features hereinabove described, reference being had to the accompanying drawings which illustrate one embodiment of the same selected for purposes of illustration, said invention being fully disclosed in the following description and claims:

In the drawings,

Fig. 1 is a perspective view of a heel attaching machine in which the illustrative work support is incorporated;

Fig. 2 is a plan view of the support;

35

Fig. 3 is a section on line III—III of Fig. 2;

Fig. 4 is a view partly in front elevation and partly in section on line IV—IV of Fig. 2;

Fig. 5 is a section corresponding to a portion of the section shown in Fig. 4 at the time when a carrier of the machine has been swung forward to a loading and unloading position or station, a fluid controlling valve of the support at that time being open; and

Fig. 6 is a section on line VI—VI of Fig. 2.

The illustrative machine is adapted for use in the attachment of a wood heel 22 (Figs. 4 and 5) to a shoe 24 mounted upon a last 26 which in place of the usual spindle or pin-hole (not shown) in the last has extending heightwise through its cone or cone portion a hollow bushing 27 provided with a bore, passage or hole 28. The machine includes a work support 29 (Figs. 1, 2, 4 and 5) comprising a spindle 31 upon which the last 26 is mounted with the spindle in the bore 28 of the bushing of said last, a driver 30 being raised through a bore or passage 33 in the spindle 31 to drive a fastening such for example as a screw 34 (Fig. 4) through the heel seat portion of the shoe and into the wood heel 22, which is forced by a clamp 35 (Fig. 1) against a fitted heel seat of the shoe, to attach the heel to the shoe. The last 26 is provided with a heel plate 40 having formed in it a hole 38 coaxial with the bushing 27 and having a diameter which is slightly less than the internal diameter of said bushing and which is slightly greater than the diameter of the driver 30. As will be explained later, during the heel attaching operation the upper end of the bushing 27 and the heel plate 40 of the last.

The work support 29 comprises a carrier 42 supported by a platform 46 journaled upon a pivot stud or shoulder screw 44 (Figs. 2 and 4) secured by a nut 45 to said platform and having an axis 43 about which the carrier may be described as being swung. The carrier is swung upon the platform 46 manually, as will be hereinafter explained, between a rear operating or heel attaching position or station, against a stud or stop 47 (Fig. 2), which is secured to the platform, and a forward, shoe receiving or loading and unloading position or station against a stud or stop 49 also secured to said platform. The platform 46 has a cylindrical depending projection 48 (Fig. 4) which fits in a cylindrical recess or well 50 in a post 52 of the machine and a flange 54 which over-

lies and rests upon the upper end of said post. Threaded into the post 52 is a locking screw 56 which is forced against the projection 48 of the platform and retains it in a position in which a slot 58 (Figs. 1 and 2) of the platform 46 is aligned with a slot 59 formed in the post 52. Swinging movement of the carrier 42 about the stud 44 and over a horizontal surface or supporting face 60 of the platform 46 between loading and operating positions or stations, is limited by the studs 47 and 49 respectively, said platform having formed on it a cam surface 66 (Fig. 5) which, in cooperation with a bell-crank lever or actuator 68, controls the action of a valve or valve plunger 70 slidably mounted upon a vertical bearing or sleeve 72 of the carrier 42. The carrier 42 has formed in it a cylindrical face or passage 74 which is concentric with relation to the vertical bearing 72 and forms with the said bearing a ring-shaped opening passage, recess or chamber 76 in which is vertically movable a mount 78 upon which is tiltedly mounted a last engaging plate 80 which has a spherical seating and affords support for the cone of the last 26 during the screw inserting operation, as will be explained later. The chamber 76 has a ring-shaped cross section.

The vertical bearing 72 has formed in it a cylindrical bore or guideway 82 for slidably receiving the spindle 31 which is arranged in concentric relation with the outer face of the bearing 72 and the cylindrical face 74 and an axis 73 of which is parallel to the axis 43. A lower portion of the chamber 76, which is formed by the carrier 42, the mount 78 and the valve 70, and which may be referred to as a lower chamber, is filled with oil and an upper chamber 86, which is formed by the mount, the valve, the spindle 31 and the sleeve 72 of said carrier, is filled with oil to a level 90. The vertical bearing 72 of the carrier 42 is secured to the pivoted portion of the carrier by screws 92, a rubber ring 94 sealing the joint between these members.

The mount 78 is constantly urged upward by a pair of springs 96 upper portions of which are arranged in bores 98 of plungers 100 slidably mounted in cylindrical guideways 102 of the carrier 42 and the lower end portions of which encircle retaining rods 104 secured to the vertical bearing 72 of the carrier. Upward movement of the mount 78 is limited by the engagement of flanges 106 of the plungers 100 with shoulders 108 of the carrier 42.

Interposed between the valve 70 and the mount 78 is a spring 110 which constantly urges a conical seat 112 of the valve 70 toward a conical face 114 of the mount 78. When the carrier is in its loading and unloading position shown in Fig. 5, the cam 66, through the bell crank lever 68 and mechanism hereinafter described, has moved the valve 70 against the action of the spring 110 to a lowered position away from the conical face 114 of the mount 78 and accordingly the lower and upper chambers 76, 86, are in communication and the mount can be forced downward under pressure exerted by the work against the last engaging plate 80, oil during such movement flowing from the lower chamber to the upper chamber.

The spindle 31 fits slidably in a bore 115 of the mount 78, extends through an enlarged hole in the last supporting plate 80 and has an enlarged cylindrical portion 116 which has an abutment face 117 and which fits slidably in a cylindrical bore or guideway 118 of the cylindrical bearing 72 and is constantly urged toward a shoulder or stop 120 of the bearing by a spring 122 interposed between the top of the bearing and a collar 124 secured by screws 126 to the spindle 31.

When the carrier 42 is in its loading and unloading position against the stop 49 the valve 70 is open, as shown in Fig. 5, and the last 26, having the shoe 24 mounted on it, is placed upon the spindle 31 which enters the passage 28 of the bushing 27 of the last, the last engaging plate 80 being swung upon the mount under pressure of the last to accommodate said last. The work is then depressed upon the spindle 31 until the upper end of the spindle engages the heel plate 40 of the last 26, said spindle at this time being held against depression by reason of the fact that the enlarged portion 116 of the spindle 31 has a diameter greater than the width of the slot 58 and accordingly the abutment face 117 is in engagement with the face 60 of the platform 46. The

operator while retaining the work depressed swings the carrier 42 with the work on it rearward into operating position against the stop 47.

It is desirable that when the heel attaching pressure is exerted against the heel seat of the shoe by the heel the mount 78 shall rigidly support the last and accordingly when the carrier is in its operating position against the stud 47 the valve 70 is held in its closed position, shown in Figs. 3 and 4, by the spring 110, thus insuring that the lower chamber 76, which is filled with oil and is cut off from the upper chamber 86, will act as a hydraulic lock and will support the mount 78 against depression. It will be noted that when the carrier 42 is in its operating position the enlarged cylindrical portion 116 of the spindle 31 is in register with a cylindrical bore or guideway 128 which is formed in the cylindrical projection 48 of the platform 46, the diameter of said cylindrical bore being greater than that of the cylindrical portion 116 of the spindle. The cylindrical guideway 128 may be described as being continuous with the slot 58 which extends into the face 60 of the support. Accordingly, it will be clear that during the attachment of the heel 22 to the shoe 24 the work is supported by the mount 78 through the cone portion of the last 26 and if during the heel attaching operation any substantial pressure is exerted by the plate 40 of the last against the spindle 31, said spindle will yield against the action of the spring 122.

The bell crank lever 68, which is actuated by the cam face 66 of the platform 46 to move the valve 70 from its closed position shown in Figs. 3 and 4 to its open position shown in Fig. 5, is secured by a screw 132 to a bearing pin 130 journaled in the mount 78. As best shown in Fig. 6, the valve 70 has secured to its upper end a pair of stepped pins 134 having notches 136 (Figs. 5 and 6) for receiving rounded ends 138 of horizontal arms of the bell crank lever 68. When the carrier 42 is in its rear or operating position against the stud 47 the valve 70 is forced by the spring 110 into its closed position against the conical surface 114 of the mount 78, the vertical arm of the bell crank lever 68 at such time being spaced from the cam surface 66. When the carrier 42 is in its forward or loading and unloading position against the stud 49, the valve 70 has been moved away from the frusto conical shoulder 114 of the mount 78 by the action of the cam surface 66 against the bell crank lever 68, thus permitting oil to flow freely from the lower chamber 75 to the upper chamber 86 to enable the mount to be depressed under pressure of work until the spindle 31 is engaged by the shoulder 39 of the heel plate 40 of the last 26.

The driver 30 is prevented from being rotated in the passage 33 of the spindle 31 by a pin 140 (Fig. 4) which is secured to the enlarged portion 116 of the spindle 31 and fits in an elongated slot 142 of the driver. When the carrier 42 is moved between its forward and rear positions the lower end of the driver 30 travels in the slot 58 of the platform 46, through the slot 59 and into the cylindrical bore 128 of the depending projection 48 of the platform 46. The driver 30 is operated by a plunger 144 which is reciprocated by power in the cylindrical bore 128 of the platform, the upper limit of movement of the driver being approximately constant since for shoes of different sizes and accordingly lasts of different heights, the driver stops substantially at the upper end of the spindle 31. The upper end of the stroke of the driver 30 may be varied if desirable by varying the upper end of the stroke of the plunger, to insert the screw 34 to a desired depth into the work.

The heel clamp 35 comprises an abutment 148 and a fork 150 which are geared together for equal movement in opposite directions and are similar in their construction and operation to corresponding parts of the heel clamp disclosed in United States Letters Patent No. 2,324,479, granted July 20, 1943 on an application filed in the name of Francis L. Brandt. The heel clamp 35 is mounted for reciprocation in an upstanding yoke 152 of the machine and is operated through suitable mechanism actuated by a treadle rod 154, for example.

In the attachment of the heel 22 to the shoe 24, the carrier 42 being in its loading and unloading position against the stud or stop 49, the operator places the last 26, upon which the shoe 24 is mounted upon the spindle 31 with the cone portion of said last in engagement with the last supporting plate 80, and manually depresses

the mount 78 until the heel plate 40 of the last engages the upper end of the spindle. The operator then manually swings the carrier 42, with the work thus depressed on said carrier, rearward until the carrier engages the stud 47. While the carrier 42 is being swung rearward the bell crank lever 68 leaves the cam surface 66 thereby allowing the valve 70 to be moved to its closed position under the action of the spring 110 and causing the mount 78 to prevent further downward movement, thus affording support for the last 26 and the shoe mounted upon it when the heel is attached to the shoe.

The heel is then positioned upon the fitted heel seat portion of the shoe and a treadle (not shown) operatively connected to the rod 154 is depressed causing the abutment 148 and the fork 150 of the heel clamp 35 to be forced with equalized pressures against the tread and rear faces respectively of the heel. If during the heel attaching operation any substantial amount of pressure, which would tend to bend the heel plate 40 of the last 26, is exerted against the heel plate, the spindle 31 will yield against the action of the spring 122.

After depressing the rod 154 by the use of the treadle to clamp the heel against the heel seat of the shoe the operator trips a one-revolution clutch (not shown) causing the driver 30 to be raised a fixed distance to drive the fastening 35 through the heel seat of the shoe 24 and into the heel 22, thereby attaching the heel to the shoe. The treadle rod 154 is then released to allow the heel clamp to be moved under the action of a spring (not shown) to its raised starting position, the carrier 42 then being swung forward against the stud 49 preparatory to removing the work from the machine.

Having described the invention, what we claim as new and desire to secure by Letters Patent of the United States is:

1. In a heel attaching machine, a carrier movable in an arcuate path between a loading and unloading position on the one hand and an operating position on the other hand, a last spindle and a mount which are arranged in concentric relation in the carrier, means for guiding in said concentric relation the spindle and the mount in the carrier in one direction in parallel paths respectively, when pressure is exerted against them by a last upon which a shoe is mounted, relatively to the carrier and relatively to each other, means for locking the spindle against movement in its path in said one direction with relation to the carrier when said carrier is in its loading and unloading position, means for permitting movement of the spindle in its path in said one direction with relation to the carrier when said carrier is in its operating position, means for locking the mount against movement in its path in said one direction with relation to the carrier when said carrier is in its operating position, and means for permitting movement of the mount in its path in said one direction when the carrier is in its loading and unloading position.

2. In a heel attaching machine, a carrier movable about a fixed axis between a loading and unloading position on the one hand and an operating position on the other hand, a last spindle, a mount, guideways which are concentrically arranged with relation to an axis generally parallel to said fixed axis and in which the spindle and the mount respectively are slidable in one direction relatively to the carrier and relatively to each other when pressure is exerted against them by a last upon which a shoe is mounted, means for locking in the carrier the spindle against movement in said one direction along its guideway when the carrier is in its loading and unloading position, means for permitting in the carrier movement of the mount in said one direction along its guideway when the carrier is in its loading and unloading position, means for locking in the carrier the mount against movement in said one direction in its guideway when the carrier is in its operating position, and means for permitting movement of the spindle in said one direction in its guideway relatively to the carrier when the carrier is in its operating position.

3. In a heel attaching machine, a carrier movable in an arcuate path between a loading and unloading position on the one hand and a heel attaching position on the other hand, a hollow last spindle and a mount, means for guiding the spindle and the mount for movement in the carrier in parallel paths respectively, when pressure is exerted against them by a last upon which a shoe is mounted, means for locking in the carrier the

spindle against movement in said one direction along its guideway when the carrier is in its loading and unloading position, means for permitting in the carrier movement of the mount in said one direction along its guideway when the carrier is in its loading and unloading position, means for locking in the carrier the mount against movement in said one direction in its guideway when the carrier is in its heel attaching position, means for permitting movement of the spindle in said one direction in its guideway relative to the carrier when said carrier is in its heel attaching position, a clamp for forcing a heel with considerable pressure against the heel seat of the shoe when the carrier is in its heel attaching position, a driver movable through the spindle to drive a screw through the heel seat of the shoe and into the heel for attaching the heel to the shoe, and means for operating the driver.

4. In a heel attaching machine, a platform, a carrier, said carrier being mounted upon the platform for pivotal movement about an axis between a loading and unloading station on the one hand and an operating station on the other hand, inner and outer concentrically arranged guideways formed in said carrier, a mount slideable in the outer guideway, a spindle slideable in the inner guideway, a valve slideable in said mount and arranged in concentric relation to said guideways, means responsive to pivotal movement of the carrier to the loading station for operating said valve to permit the mount acted on by the pressure of the work against it to yield relatively to the carrier and to cause the spindle to be rigidly secured to the carrier, and means responsive to swinging movement of the carrier to said operating station for moving said valve to a position in which the mount is secured against movement with relation to the carrier and the spindle is yieldable relatively to the carrier.

5. In a heel attaching machine, a work support comprising a carrier movable between shoe receiving and heel attaching positions and having a sleeve, which has a central cylindrical bore, and which forms with other parts of the carrier a recess of ring-shaped cross section which is concentric with said bore, a spindle which is slideable in said bore and which is constructed and arranged to be received in a hollow bushing extending heightwise through a last upon which a shoe to which a heel is to be attached is mounted, a valve plunger slidably mounted on said sleeve and in said recess, a mount which is slideable on said carrier and in said recess and forms with the valve plunger, the spindle and the carrier an upper chamber and which forms with the carrier and the valve plunger a lower chamber, a spring for constantly urging the spindle to a raised position with relation to the carrier, resilient means for constantly urging the mount to a raised position with relation to the carrier, fluid which fills the lower chamber and partially fills the upper chamber, means for locking the spindle against movement in one direction in said bore when the carrier is in its shoe receiving position, means for permitting movement of the spindle in said one direction in said bore when the carrier is in its heel attaching position, and means responsive to movement of the carrier between shoe receiving and heel attaching stations for retaining the valve plunger in open and closed positions respectively in order to permit the mount at the shoe receiving position to be depressed against the action of said resilient means by the last to enable the last to be forced against the spindle then rigidly secured to the carrier and in order to cause the mount at the heel attaching position rigidly to support the last, the spindle at such time being movable under pressure of the last.

6. In a heel attaching machine, a platform having a

bore, a power actuated plunger movable lengthwise of said bore, a carrier having a guideway and a stop, a work positioning spindle which has a passage and is movable lengthwise of said guideway, a spring for constantly urging said spindle to a position against said stop, a driver which is movable in the passage of the spindle and is operated by said plunger, a mount slideable in the carrier and arranged in concentric relation with the spindle, hydraulic means for locking the mount to the carrier and for releasing the mount for movement relatively to the carrier, and an actuator which is mounted on and is movable on the carrier and which is adapted to control said hydraulic means, said carrier being pivotally mounted upon the platform for movement between a loading and unloading position on the one hand, and an operating position on the other hand, means for locking the spindle against movement in one direction in said guideway when the carrier is in its loading and unloading position, said actuator being moved to one position in response to movement of the carrier to its loading and unloading position to cause said hydraulic means to allow movement of the mount in said one direction in the carrier under pressure of work slideable on the spindle, and means for permitting movement of the spindle in said one direction in said guideway under pressure of the work when the carrier is in its operating position, said actuator being movable to a second position in response to movement of the carrier to its operating position to cause said hydraulic means to lock said mount against movement in said one direction under pressure of the work.

7. In a heel attaching machine, a platform having a supporting face, a guideway and a slot which is continuous with said guideway and extends into said face, stops secured to the platform, a carrier movable upon said platform between operating and loading positions determined by said stops respectively, said carrier having a bore which is in register with said guideway when the carrier is in operating position, a spindle movable in said bore, a spring for continuously urging said spindle into a position in which one end of said spindle is in substantial alignment with said face of the platform, a driver movable through the spindle, said carrier having a passage which is concentric with the spindle and the driver, a mount movable along said passage and adapted to support a shoe on a last, hydraulic means for securing the mount against movement in said passage and for permitting movement of said mount in said passage, a cam secured to the platform, said spindle having an abutment face, which is in engagement with said face of the platform when the carrier is in loading position, and being shaped and arranged for reception in a spindle hole extending through the cone of the last until such time as said spindle is engaged by a shoulder of said last, thereby rigidly supporting said last and the shoe mounted on it, means for permitting movement of the spindle against the action of said spring in one direction lengthwise of the bore of the carrier and into the guideway of the carrier when the carrier is in its operating position, and mechanism actuated by said cam for causing, when the carrier is in loading position, said hydraulic means to allow the mount to slide on the carrier, under pressure of the last, to a predetermined position until said shoulder of the last engages the spindle and for causing, when the carrier is in its operating position, the hydraulic means to lock the mount against movement in said one direction on the carrier.
